UNITED STATES PATENT OFFICE.

ELIZABETH E. BRINSER, OF ELIZABETHTOWN, PENNSYLVANIA.

AUTOMATIC PATTERN STAB.

Application filed March 16, 1927. Serial No. 175,910.

In cutting shoes by hand it is customary to use a pattern of the part to be cut from the leather or other goods entering into the shoe, and to mark superficially the cut out part so as to guide the stitcher in stitching. This marking is called "stabbing", and it is commonly accomplished by providing the pattern with eyeleted or other holes through which the cutter inserts an awl or other marking tool and by it impresses superficial marks on the material to guide the stitcher in assembling the parts to be united by stitching. The use of an awl does not always give accurate results, because of the personal equation incident to its use, and hence the finished shoe is more or less imperfect. It is highly desirable that the marking be done accurately, and to this end I provide, by my invention, stabs rigidly applied to the pattern, at predetermined points, so that the cutter may cut the material and stab it without using an extraneous tool for the stabbing.

The invention consists of a pattern having fixedly applied to it pointed devices, herein referred to as "stabs", which are arranged therein so as to enable the cutter to define the line on which the stitcher must unite parts, such as uppers or vamps, in proper relation to other parts to insure a perfect shoe. The stabs project from both sides of the pattern so that one pattern may be used for both rights and lefts, as I will proceed now to explain and finally claim.

In the accompanying drawings illustrating the invention, in the several figures of which like parts are similarly designated, Figure 1 is a plan view of a pattern of part of a shoe, having my stabs applied thereto. Fig. 2 is a cross-section on line 2-2, showing at the right-hand side a stab in elevation with its securing element in section and at the left-hand side showing these parts entirely in section. Fig. 3 is an elevation of the stab detached, and Fig. 4 is a cross-section of the securing element. Fig. 5 is a sectional elevation showing the stab in elevation and its securing element in position to be assembled upon a pattern, a fragment of the pattern being shown in section. Fig. 6 is a view similar to Fig. 5 with the parts assembled. Fig. 7 is a view like Fig. 6, illustrating a modification. Fig. 8 is a plan view of a different form of securing element.

Without thereby limiting the invention to any particular part of a shoe, I have herein

shown it as applied to a vamp pattern. This pattern 1 is made of fiber-board or other rigid shape-retaining material, and preferably has its edge provided with a metal binding 2, so as to resist the wear of the cutter's knife when using the pattern over a piece of shoe material, such as leather, to cut out the part.

My invention contemplates the use of stabs consisting of a body portion 3, both ends 4 and 5 of which are tapered and blunt-pointed, and one end provided with a laterally extending flange 6 and the other end provided with a groove 7, so that the body may be passed through a hole in the pattern until the flange 6 rests flat upon the face of the pattern and then the securing element 8, here shown as a washer, is applied to the groove 7 by forcing the element 8 over the end 5, as indicated in Fig. 5, and then flattening out this element 8, as indicated in Fig. 6. The element 8 is shown as made as a concave washer which may be flattened out when the edge of its hole is forced inwardly into the groove 7, and against the material of the pattern.

Instead of making the body portion 3 with an integral flange 6, it may be provided with one groove 7 to receive the securing element 8 and the other end of the body may be likewise provided with a groove 9 in which is pressed a similar securing element 10, as shown in Fig. 7.

Instead of making a securing element such as those already described, it may be made, as shown in Fig. 8, as a radially slotted washer 11.

In either construction of securing elements the resilience of the metal serves to keep the element in retaining engagement with the body.

It will be observed that the stab has both ends alike, and these ends project from opposite sides of the pattern, so that the pattern may be used reversely for stabbing purposes in cutting and marking both right and left shoe portions.

As already indicated, the invention is not limited to use on leather, and it is not limited to its use on shoe parts, regardless of their material, but it may be used on parts for purses, pocket books, bags, and other containers that are made up of parts which are stitched together.

By means of a stab constructed as de-

- scribed, the correct marking of a pattern is absolutely ensured, because the stabs are fixedly applied to the pattern and extend in the same plane from both sides. When 5 the pattern is placed on the material the operator simply presses it sufficiently to make the correct impression. Obviously the operator must apply sufficient pressure to the pattern when cutting to prevent it from 10 slipping, and with slightly additional pressure, he can make the impression on the material. Because of this mode of operation, I have designated my device as an automatic pattern stab.
- 15 2. The ends of the stab are rounded or blunt-pointed so as not to mar or deface the material being marked as the pattern is moved into position on the material.
- The foregoing and other variations are 20 permissible within the principle of the invention and the scope of the claims following.
- What I claim is:—
1. A pattern stab, having a body provided 25 with blunt ends and adapted to be applied to a pattern with the ends projecting from opposite sides, and means applied to the

body between its ends and the pattern to secure the body to the pattern.

2. A pattern stab, comprising a body having 30 its opposite ends blunt-pointed and adapted to be applied to a pattern so that its ends extend from opposite sides thereof, one end having an adjacent integral flange to rest on one side of the pattern and the other 35 end provided with a circumferential groove and a resilient washer forced into engagement with said groove.

3. The combination with a pattern, of a 40 stab, comprising a body having its opposite ends blunt-pointed and adapted to be applied to the pattern so that its ends extend from opposite sides thereof, one end having a flange to rest on one side of the pattern and the other end provided with a circumferential 45 groove exposed on the other side of the pattern and a resilient washer forced into engagement with said groove and flattened out against the pattern.

In testimony whereof I have hereunto set 50 my hand this 15th day of March, A. D. 1927.

ELIZABETH E. BRINSER.
